CRANKSHAFT GRINDER

Harry T. Rutherford, Baltimore, Md., assignor to
 Vickers, Incorporated, Detroit, Mich., a corpora-
 tion of Michigan

Application August 19, 1946, Serial No. 691,554

9 Claims. (Cl. 51—241)

1

The present invention relates to a portable crank shaft grinding tool and especially to a grinding tool adapted to re-condition the connecting rod portion, or throw, of a crank shaft.

The improved grinder comprising the present invention is primarily adapted for use in automobile, truck, and other motor vehicle engines. Because of the compactness of the present day automobile engine and its location in relation to the chassis, it has become practically impossible to work on these throw portions without removing the engine from the vehicle. It is with this in mind that the present tool has been developed. The tool is so designed and constructed that by removing the cylinder head, piston and the connecting rod from the engine it may be inserted through the cylinder and operated within the space normally occupied by the piston and connecting rod.

While the grinding tool is especially designed for engines of motor vehicles, the principles of the invention are applicable to other uses and the grinder may be employed on engines in general regardless of their nature.

The connecting rod receiving portion of the crank shaft may for purposes of convenience be designated as bearing, throw, or shaft.

The primary object of the invention is to provide a grinding tool of such dimensions that it may be placed in operation through the cylinder, after the removal of the cylinder head, piston and the connecting rod, for grinding the connecting rod receiving portion of the crank shaft without removing the engine from the vehicle, or the shaft from the main engine bearings.

Another object of the invention is to so construct the device that the grinding wheel may be more accurately regulated during the grinding operation.

A further object of the invention is to provide an improved method of grinding the surface of the connecting rod receiving portion of the crank shaft.

Still a further object of the invention being to provide a grinding tool which is held in operating position by the engine cylinder and the corresponding connecting rod receiving portion of the crank shaft.

Other objects and advantages of the invention not at this time more particularly enumerated will become readily apparent as the nature of the invention is better understood. The novel construction, combination and arrangement of parts will be clearly shown in the accompanying sheets of drawings forming a part of the specifications, in which:

2

Figure 1 is an assembly view of the grinding tool together with a fragmentary view of a typical engine cylinder, illustrating the manner in which the tool is used and its relative position in relation to the cylinder and the corresponding connecting rod receiving portion of the crank shaft.

Figure 2 is a sectional view taken along the line 2—2 of Figure 1.

Figure 3 is an enlarged view in elevation of the form of grinding tool shown in Figure 1.

Figure 4 is a top plan view of the same.

Figure 5 is a diagrammatic plan view of the grinding wheel and portions of the crank shaft showing the grinding surface of the wheel rotating substantially at a tangent to the bearing surface of the shaft and to one side of the center line thereof.

Figure 6 is a view similar to Figure 5 in which the axis of the rotating grinding wheel is perpendicular with the center line of the shaft.

Figure 7 is a view taken along the line 7—7 of Figure 3.

Figure 8 is a fragmentary view in elevation of the lower end of the tool looking from the right in Figure 3.

Figure 9 is a sectional view taken along the line 9—9 of Figure 7.

Figure 10 is a fragmentary view in elevation of a modified form of shaft supporting means.

Figure 11 is a fragmentary view in elevation of the modified form of shaft supporting means looking from the right in Figure 10.

Figure 12 is a fragmentary sectional view taken along the line 12—12 of Figure 10.

Figure 13 is a view in elevation of a modified form of variable expansion guide member for guiding the outer end of the tool.

Figure 14 is a top plan view of same.

Figure 15 is a sectional view taken along the line 15—15 of Figure 13.

Figure 16 is an enlarged fragmentary view partly in section of the actuating arm and fastening means for the variable expansion member of the guide member.

In the following detailed description like numerals will designate like parts throughout the several views.

The general organization of the invention is best understood by referring first to the form shown in Figures 1 to 9. In the drawings a typical crank shaft is designated at 2 and its connecting rod receiving portion at 2'. In the present form the invention comprises a crank shaft positioning means having a U-shaped frame formed by the arms 4 and 4', which are adapted

to extend downwardly through the cylinder and over the connecting rod receiving portion of the crank shaft. Connecting the two outer ends of the U-frame is a member 6, one end being hinged at 8 to the side member 4 of the U-frame, the other end being secured to the opposite frame member 4' by the pivoted threaded bolt 10 and knurled nut 12. At the closed end of the U-frame and integral therewith is a hollow tube member 14 which is slidably receivable over a tube member 16 and is secured thereto by a set screw 18. Extending through the tube 16 is a drive shaft 20 the inner end of which is threaded and adapted to extend slightly within the end of the base of the U-frame. Threadably receivable on the threaded end of the drive shaft is a grinding wheel 22. The grinding wheel is preferably driven by a motor 24 through a conventional flexible shaft 26 extending inwardly through the cylinder which is in turn connected with the outer end of the shaft 20. The shaft 20 is provided with appropriate thrust bearings (not shown) adjacent the grinding wheel to prevent any end-play of the shaft and to the wheel which is carried by the shaft.

The hinged member 6 carries the means by which the grinding wheel is brought in contact with the portion 2' of the shaft. Within the upper portion of the hinged member 6 there is provided a rectangular slot 28. Slidably fitting within this slot is a support 30 having at its upper surface laterally extended flange members 32 and 34 for contacting the shaft at the points 32' and 34' adjacent its lower arc. Extending downwardly and centrally of the slot 28 is a threaded aperture 36 and threadably receivable within the aperture is a screw 38. The screw is provided with a knurled head 39. Secured to the frame 6 is a spring 40, the outer edge of which engages the knurled head 39 of the screw 38 for retaining the screw in adjusted positions. The base portion of member 30 is provided with an aperture 42 for receiving a reduced portion 38' of the screw member 38. A shoulder 44 is formed between the reduced portion and the threaded portion of the screw and is adapted to bear against the under surface of the base portion of the member 30. By rotating the screw 38 within the aperture 36 the support 30 may be adjusted relative to the depth of the slot 28 of the hinge member 6 and the grinding wheel 22, which brings the grinding wheel in contact with the bearing surface.

Located approximately midway between the grinding wheel and the support 30 and adapted to contact the circumference of the shaft is a roller 25, which is carried on an adjustable pin 21. The pin is supported within an aperture 31 in the U-shaped member 4, and is held in position by the set screw 29.

The width of the support 30 is substantially the same as the width of the connecting rod bearing surface as shown in Figures 8 and 9. The flange members 32 and 34 are provided on their upper surface adjacent the outer edges with ribs 46 and 46'. These ribs are adapted to rest against the shaft adjacent its outer edges in order to support the element 30, which regulates the cut of the tool. The reason for supporting the shaft adjacent its outer edges on these rib members is that these portions are more likely to be cylindrical in worn shafts than the portion of the shaft carrying the main thrust of the connecting rod.

The grinding wheel 22, like the supporting member 30 is also of substantially the same diam-

eter as the width of the shaft surface 2'. For the first grinding operation the axis of the wheel is offset in a line perpendicular to the center line of the shaft bearing. In this position the grinding wheel will grind a major part of the bearing, leaving a ridge 48 and 48' (see Fig. 5) adjacent the sides of the bearing upon which the rib members 46 and 46' are supported.

In order to grind these ridge members down to a point to conform with the first ground surface the wheel must be subsequently operated with its axis perpendicular to the center line of the bearing as shown in Figure 6.

To locate the grinding wheel eccentrically of the shaft, the supporting member 30 and the arm members 32 and 34 are so constructed as to support the center line of the shaft 2' slightly to one side the center line of the rectangular slot 28 and also to one side of a line extending through the axis of the drive shaft 20. This portion is shown in full lines in Figures 3 and 5. By reversing the member 30 within the slot 28, the center line of the shaft will be moved to the right as shown by the dotted line in Figure 3 and in line with the axis of the grinding wheel, as shown in Figure 6.

Adjustably receivable over the opposite or outer end of the wheel supporting tube member 16 is a sleeve or tube member 50, similar to the tube 14. The tube 50 is held in adjusted position by the set screw 52. Adjacent the upper or outer end of the tube 50 is a pair of oppositely disposed hollow arm members 54 and 56. Fitted within the arm members are suitable pin members 58 and 60, which extend outwardly from the arm members and having their opposite ends pivotally supported in oppositely disposed arbors 62 and 64, which are in turn rigidly secured to the inner wall of the upper or outer guide member 74. The pins 58 and 60 are rotatably supported within the arbors by screws 66 and 68 operating within the circumferential grooves 70 and 72 of the pin members. A key 76 prevents the sleeve members 14 and 50 from rotating upon the tube 16 and retains the axis of the pin members 58 and 60 parallel with the supporting arms 32 and 34 and likewise parallel with the center line of the connecting rod receiving portion of the crank shaft during the grinding operation.

The outer guide 74 comprises a cylindrical piston-like member adapted to slide within the cylinder similar to the operation of the engine piston. In order to use a single guide member for a number of different size cylinders, the guide member is provided with means for adjusting the guide to the various size cylinders. One form of the adjustable guide is shown in Figures 3 and 4 and comprises a series of threaded studs 80, 80', 81, 81', 82, 82', 83 and 83' which may be extended outwardly beyond the outer surface of the guide 74 for varying its size. The guide 74 may also be adjusted laterally along the pins 58 and 60 by means of the screws 46 and 46' for grinding shaft bearing surfaces which are slightly offset.

A modified form of shaft positioning means is illustrated in Figures 10, 11 and 12 and comprises in particular a modified form of hinge member which may replace the hinge member 6 as shown and described in Figure 3. The modified member 86 is attached to the U-frame 4 and 4' as described for the member 6 and is provided with a rectangular slot 88 adjacent its upper surface similar to the slot 28 as shown in the member 6. Slidably fitted in the slot is a rectangular member 90 which is adjustable along a line parallel

with the axis of the drive shaft and grinding wheel. To make these adjustments there is a screw 92 extending through the base of the slot having a knurled head 93 and a retension spring 94, which is constructed and operated in substantially the same manner as that described for the adjusting screw 38 in Figure 3. Supported within a semi-cylindrical recess 86' in the upper surface of the member 86 is a support 95 for the connecting rod receiving portion of the crank shaft. The support 95 is also provided with flange members 87 and 89 and ribs 91 and 93 for supporting the shaft in substantially the same manner as the bearing support 39 in Figure 3. The support is prevented from lateral movement by the threaded pin 93 operating within the slot 99. This arrangement is adapted to allow the shaft support to rock through a predetermined arc for allowing for the first and second grinding operation which has been previously described. For positioning the shaft portion 2' in relation to the grinding wheel 22 the roller 25 is utilized as shown and described in Figure 3, except in this form the full thrust of the rotating shaft is borne by the roller, whereas in the support 39 shown in Figure 3 the major portion of the thrust is taken up by the support.

Figures 13 to 16 show a modified form of an adjustable guide member. The guide member comprises a cylindrical frame 100 having inwardly disposed rim members 106 and 108 extending around the upper and lower edges thereof respectively. Located adjacent the outer circumferential edge of the frame are a plurality of eccentrically mounted cylinder members 101, 102, 103 and 104. These eccentric cylinders are pivoted within the upper and lower rim members and adjacent the outer edge thereof and are supported upon journals 110, 111, 112, and 113 and journals 119, and 113'. Secured to the top journals are arms 115, 118 by pins 120 and 120'. There is provided in the upper rim member 106 semi-circular slots 122 and 123 of approximately 170°. Operating within the slots are bolts 124 and 126 carried by the outer ends of the arms on which are threaded nuts 127 and 128 respectively to provide fastening means for the eccentric members. To adjust these members the outer end of the arm is moved along the slot and secured in its appropriate position by the above named fastening means. The bolt 124 is flattened at 130 as shown in Figure 16 to prevent it from turning when tightening the nut 127. The means for attaching the modified guide to the tool are substantially the same as described in Figure 3, the pins 58 and 60 extending outwardly from the tube 50 to engage arbors 55 and 55' on the frame of the guide and the tube member 50 being secured to the tubular drive shaft support 16 by means of a set screw, or other suitable means.

The tool is further provided with a pair of tension springs 129 and 131 which are adapted to urge the tool outwardly toward the outer end of the cylinder, keeping the shaft support forced against the shaft, the inner ends of the springs 132 and 133 being connected to the pin members 58 and 60, and the outer ends of the springs being connected to a supporting bar 134. The outer end of the bar is formed at right angles and extends over the top of the cylinder. The angular portion of the bar to which the outer ends of the springs are attached is preferably directly above the cylinder during the grinding operation. In order to support the bar 134 upon the engine, there is a hollow base member 136

which is fastened to the top of the cylinder block by a stud 135 and nut 135' engaging the foot 136' of the base into which the bar is adjustably secured in position by a thumb screw 138.

To place the tool in operation, the tool is assembled as shown in Figure 3, the outer guide and the shaft positioning means for the connecting rod receiving portion of the shaft are fastened to the grinding wheel and drive shaft supporting tube 16 in their approximate location. The hinge member is released from one side of the U-frame by the screw 10. The tool is then inserted into and through the cylinder 140 as shown in Figure 1. The crank shaft is then inserted between the U-frame member 4 and 4' and the hinge member is fastened in place with the bearing support 30 in its offset position as shown in full lines in Figure 3 for the first grinding operation. While in this position the roller 25 is moved in contact with the shaft 2' and fastened by the screw 29. At this point in the preparation the grinding wheel should be slightly above the upper surface of the crank shaft. The springs 130 and 131 are fastened between the pins 58 and 60 and the bracket 134 bringing and retaining the support 30 in contact with the shaft. To begin the grinding, the grinding wheel 22 is set in motion in the direction as indicated by the arrow in Figure 3. The wheel is then brought in contact with the shaft by moving the support 30 outwardly in the slot by operating the screw 38. As the wheel is brought in contact with the shaft the crank shaft is slowly rotated in the direction of the arrows as indicated on the shaft in Figure 3. The shaft is rotated by a separate electric motor or other suitable means at a comparatively slow rate of speed.

As the tool is carried around the crank shaft through the guide moves within the cylinder 140 in substantially the same manner in which the piston operates, the outer end of the grinding wheel supporting member 16 being pivotably connected with the guide member at a predetermined point within the cylinder area. Subsequent cuts are made by the grinding wheel as the supporting member 30 is further advanced upwardly within the slot. After the bearing has been ground to a predetermined diameter while in its offset position there remains the outer portions of the bearing 48 and 48' to be ground to the level of the first ground portion. To accomplish this the roller 25 is released by the screw 29 and moved back to the point indicated by the dotted line 2'', where it is again fastened in place. The hinge member is again lowered and the support 30 is reversed within the slot 28 and at the same time lowered to a point adjacent the bottom of the slot 28. The hinge is then tightened in place, the shaft portion 2' will then take the position as indicated by the dotted line 2''. The grinding wheel axis is then in a position perpendicular to the center line of the shaft. The second grinding operation may now be carried out in substantially the same manner as the first grinding operation. When the second grinding operation is completed the shaft will appear as in Figure 1 and will be of the same diameter throughout its entire surface.

It will be noted that during both the first and second grinding operation, that the springs 131 maintain the tool in contact with the bottom of the crankshaft throw. In case the throw is non-circular due to wear, as is usually the case, there will be some positions of the crankshaft where a given setting of the micrometer adjust-

ment screw 39 will leave the grinding wheel out of contact with the crank throw. By providing the springs 131 to constantly bias the tool upwardly, the grinding face is thus maintained at a predetermined distance from the lower face of the crankshaft throw along its edges.

The form of the invention is not to be limited to the exact arrangement of parts shown in the accompanying drawings or described in this specification as various changes in the details of construction may be resorted to without departing from the spirit of the invention. Only in so far as the invention has been particularly pointed out in the accompanying claims is the same to be limited.

I claim:

1. A crank shaft grinding tool adapted to be inserted within a cylinder of an engine having a crank shaft comprising, a grinding wheel and a drive shaft therefor, a positioning member at one end of said tool adapted to reciprocate within the cylinder and having means associated therewith for varying the size thereof and a positioning member at the opposite end of the said tool for engaging the crank shaft, means for urging the tool in the direction of the cylinder positioning means and means associated with the crank shaft positioning means for supporting the grinding wheel in proper grinding relationship with the crank-shaft as the said crank shaft is rotated in its supporting bearings.

2. A crank shaft grinding tool comprising an adjustable guide member adapted to be inserted within the cylinder of an engine having a crank shaft, a grinding wheel and a drive shaft therefor, means for pivotably supporting the said grinding wheel outwardly from one end of the said guide, a crank shaft positioning means associated with the grinding wheel support and extending beyond the said grinding wheel, a crank shaft support carried by said crank shaft positioning means and adapted to be positioned on the opposite side of the said shaft from the wheel and means for adjusting the shaft support relative to the cutting surface of the said wheel.

3. A crank shaft grinding tool adapted to be inserted within a cylinder of an engine having a crank shaft comprising, a grinding wheel rotating in a plane parallel to a tangent to the surface of the crank shaft, a drive shaft for said grinding wheel, a supporting member for said drive shaft and grinding wheel, a crank shaft positioning member adjustably secured to the end of the drive shaft support adjacent the grinding wheel, and a cylinder positioning member secured to the outer portion of the said drive shaft support, the crank shaft positioning member extending around the crank shaft to support the crank shaft opposite the said grinding wheel, and means for adjusting the said support in a line parallel with the axis of the said grinding wheel and means for urging the tool in the direction of the cylinder positioning member.

4. A crank shaft throw bearing surface grinding tool adapted to be inserted within a cylinder of an engine having a crank shaft, comprising a grinding wheel and a drive shaft therefor, a supporting member for said drive shaft and grinding wheel, a crank shaft positioning member secured to the end of the drive shaft support adjacent the grinding wheel, said positioning member extending around the crank shaft to support the crank shaft opposite the grinding wheel, a support for receiving the said crank shaft bearing portion of substantially the same

length as the said bearing portion, said support having means adjacent its outer edges for contacting and supporting the said shaft adjacent the outer edges of the bearing surface, means associated with the said crank shaft support for adjusting the said support in a line parallel with the axis of the said grinding wheel and relative to the said crank shaft positioning means and means for urging the tool in the direction of the said grinding wheel and against the crank shaft supporting means.

5. A power tool for grinding the throws of an engine crankshaft while positioned in the engine, comprising a member engageable with the shaft throw and having a bearing for a grinding wheel shaft extending perpendicularly to the crank-shaft and on the side thereof toward the engine cylinder, a grinding wheel shaft mounted in the bearing and carrying a grinding wheel with its flat end face tangent to the surface of the crank-shaft throw, means extending into the engine cylinder for driving the grinding wheel shaft, and guide means movable along the cylinder walls for preventing rotation of the tool as the crank-shaft is rotated.

6. A power tool for grinding the throws of an engine crankshaft while positioned in the engine, comprising a member engageable with the shaft throw and having a bearing for a grinding wheel shaft extending perpendicularly to the crank-shaft and on the side thereof toward the engine cylinder, a grinding wheel shaft mounted in the bearing and carrying a grinding wheel with its flat end face tangent to the surface of the crank-shaft throw, means extending into the engine cylinder for driving the grinding wheel shaft, and means engaging the engine block forming a guide for the tool and arranged to permit sliding of the tool longitudinally of the cylinder axis and swinging in a plane perpendicular to the crankshaft axis but rigidly positioning the tool against movement angularly in the plane common to the cylinder and crankshaft axes.

7. A power tool for grinding the throws of an engine crankshaft while positioned in the engine, comprising a bearing for a grinding wheel shaft, a power driven shaft supported in said bearing and carrying a face-contact grinding wheel at its end, means for locating the face of the grinding wheel comprising a yoke attached to the bearing and engaging the crankshaft throw to position the wheel at an adjustable predetermined distance from the center of the throw and on the side toward the engine cylinder, said means also including a reciprocating and pivoting guide engaging the engine block to position the wheel axis against displacement angularly in the plane common to the crankshaft and cylinder axes.

8. A power tool for grinding the throws of an engine crankshaft while positioned in the engine, comprising a bearing for a grinding wheel shaft, motor driven means extending into the engine cylinder and terminating in said bearing, a face-contact grinding wheel driven thereby, means for locating the face of the grinding wheel comprising a yoke attached to the bearing and engaging the crankshaft throw to position the wheel at an adjustable predetermined distance from the center of the throw and on the side toward the engine cylinder, said means also including a reciprocating and pivoting guide engaging the engine block to position the wheel axis against displacement angularly in the plane common to the crankshaft and cylinder axes.

9. A power tool for grinding the throws of an

engine crankshaft while positioned in the engine, comprising a power driven grinding wheel, means contacting the crankshaft on only the side opposite the cylinder for positioning the wheel tangent to the crankshaft throw on the side adjacent the cylinder, driving means extending into the cylinder for rotating the grinding wheel, and guide means engaging the engine block for locating the tool against angular displacement in the plane common to the crankshaft and cylinder axes.
